UNITED STATES PATENT OFFICE.

FRANK L. O. WADSWORTH, OF PITTSBURGH, PENNSYLVANIA, ASSIGNOR TO HUGHES
TOOL COMPANY, OF HOUSTON, TEXAS, A CORPORATION OF TEXAS.

ROTARY BORING DRILL.

1,408,549.

Specification of Letters Patent.

Patented Mar. 7, 1922.

Original application filed May 26, 1919, Serial No. 300,004. Divided and this application filed May 10, 1920. Serial No. 380,033.

To all whom it may concern:

Be it known that I, FRANK L. O. WADSWORTH, a citizen of the United States, residing at Pittsburgh, Pennsylvania, have invented a certain new and useful Improvement in Rotary Boring Drills, of which the following is a full, clear, and exact description, such as will enable others skilled in the art to which it appertains to make and use the same.

This invention relates to a particular species of the construction generically disclosed in my copending application No. 300,004, filed May 26, 1919, now Patent Number 1,374,867 issued April 12th, 1921, from which this application has been divided. It relates to improvements in rotary boring drills of the roller bit type and more particularly to drills which are provided with disc shaped cutters, and which are designed for drilling oil or water wells of moderate depth. Drills of this general character generally comprise a head which is threaded at the upper end for attachment to a rotary drill stem, and which is provided at its forward end with a pair of disc shaped cutters that are mounted to rotate on axes transverse to the longitudinal axis of the head. The matter which is cut away and disintegrated by the drill is washed away from the cutters and carried to the surface by a stream of flushing water introduced under pressure through the hollow drill stem and through channels in the head of the bit.

One object of my invention is to mount the cutters of the drilling tool, in such a manner as to attain the most effective cutting and disintegrating action when the drill is operated in strata of varying hardness.

Another object of these improvements is to provide cutting members, whose form and arrangement are such that a part of the cutting operation will be performed by the rear or following edges of the said members.

Still another object of this invention is to provide the cutting members with teeth of such form as to facilitate the rotation of the cutting elements upon their own axes as the drill head is revolved.

A further object of my present invention is to arrange the cutting members in such relation to the axis of the drill head that the side thrust of the cutting strains is directed toward the said axis, instead of away from

it, as in the usual form of disc drill construction.

Additional objects and purposes of these improvements are the provision of a novel form of cutting edge on the outer faces of the rotatable disc members and the provision of a novel bearing support for the said members. Other objects and advantages of my improvements will more clearly appear in the following description of several illustrative embodiments of my invention.

In the drawings, wherein like characters refer to like parts throughout the different views, Fig. 1 is a side view, partly in section, showing the preferred embodiment of my invention; Fig. 2 is a transverse section on the double plane 2—2 of Fig. 1; Fig. 3 is a side elevation of the head, as viewed at right angles to the plane of Fig. 1.

In the preferred embodiment of my invention, as depicted in Figs. 1, 2 and 3 of the drawings, the cutting members 13^y—13^y are mounted directly opposite each other upon the base of the head, 11. The head is made up of a cylindrical shaped body having an upper threaded shank 12, for attaching it to the drill stem by which it is operated. The revolvable cutter members are housed in a central slot in the base of the head. The sides of the housing slot are flared outwardly; and, each cutter is mounted on a separate inclined pin or shaft 14^y, which is provided with an outer thickened head 27^y fitting within a corresponding recess in the outer face of the head.

In this organization the inner ends of cutter supports, 14^y, are reversely beveled,—as shown in Fig. 1—and the cutters, which are mounted upon these supports, are spaced apart by a central wedge shaped washer 38. The parts are held in their assembled position, in the head, by means of a bolt 36 that is threaded into the right hand shaft 14^y; and after the parts are drawn tightly into position, by screwing home this bolt, the threaded end thereof is headed over to prevent its accidental loosening. When it is desired to remove the parts, the headed over portion is cut away with a file or cold-chisel; and when the parts are re-assembled again a new bolt is, if necessary, used for again securing them in place in the manner just described. In this construction a stream of

flushing water is supplied through a single central tube 18^y, which leads from the top of the drill head to the slot in which the disc members are housed and partially shrouded. The pocket for containing the lubricant is formed by a chamber surrounding this central tube; and passage ways 20^y lead from the lower end of this pocket to corresponding grooves or apertures, formed 10 in the shafts 14^y and communicating, at proper points, with the bearing surfaces of the bushings 32^y. This lubricant pocket 41 is closed at the top with a suitable screw cap 40 which is preferably threaded on the tube 18^y, although it may, if desired, be threaded directly into the upper end of the lubricant chamber in the drill head.

The disc members of this embodiment of my invention may be made solid; but, as indicated in plan view in Fig. 2, they are preferably each composed of two parts, which are capable of revolving independently on the shaft 14^y, or on the bushing 32^y. In this case the rolling or revolving 25 movement of the inner parts, which carry the advancing edges 25^y, may be slightly different from the rolling movement of the outer parts, which carry the following edges 26^y; and as a result of these differential movements,—which are produced by the engagement of the peripheral faces of the parts with the bottom of the bore hole at different distances from the axis of rotation—a more effective cutting action of the 30 independently moving edges, and a more effective crushing action of the peripheral faces between those edges, may, under certain conditions, be secured. The outer faces of the discs are recessed, to provide sharp 40 cutting edges 26^y on the rearward following sides of the revolving members.

The operation of my improved boring drill will be readily understood. The head of the bit is rotated in a clockwise direction, 45 and during such rotation the sharp cutting edges, and the cooperating toothed surfaces, on the opposite sides of the revolvable disc members act concurrently and conjointly to shear away the material from the sides and bottom of the hole; and the broad peripheral surfaces of the cutters act also to disintegrate the material so removed, and quickly reduce it to such a fine state of comminution that it may be easily washed away 50 by the stream of flushing water which is projected downwardly through the channels in the rotating head. The shearing and cutting action of the oppositely inclined teeth, on the peripheral edges of the disc members, 55 induces a semi-positive revolution of those members in the same direction in which they tend to roll on the bottom of the hole, and thus causes them to present a continually changing cutting and crushing surface to 60 the material being drilled. The provision

of the recesses on the outer sides of the disc members, and the resultant cutting action of the rearward following sides thereof, produces an inwardly directed thrust on the revolving members, that serves to hold them 70 in close operative engagement with the central portions of the head supports; and this relieves to some extent the transverse strains on the shaft bearings, and materially stiffens the relatively thin disc elements against the 75 pressures of the cut.

The division of each cutter member into two parts allows a differential movement of the inner and outer disc elements; and the inclined teeth on the peripheries of the independently rotatable discs are permitted to act more directly in assisting the rotation thereof. In these embodiments the inner faces of the inner discs shear away the material from the sides of the hole on the forward advancing sides of the rotatable members; and the outer recessed faces of the outer discs shear away the material which is in engagement with the rearward following sides of those members; and the loose 85 material thus removed is very rapidly disintegrated and pulverized by the differential rolling movement of the toothed peripheral surfaces over the bottom and side walls of the bore cavity.

The operative advantages of my present improvements will now be apparent: The provision of sharp cutting edges on the outer faces of the cutter members and the shaping of the disc peripheries to conform to the 90 curvature of the hole, makes it unnecessary to provide any clearance for the discs by offsetting them one from the other, as is now customary; and as a result of this the rapidity of the cutting and crushing operations is 100 increased; the number of points of contact between the revolving members and the walls of the bore hole are substantially doubled; and the steadiness of action of the 105 rotating drill head is thereby materially improved. The provision of oppositely inclined, or "herring bone," teeth on the peripheries of the cutting discs, and the positioning of these teeth in such relation thereto that the rotation of the drill head produces a semi positive rolling or revolving movement of the said discs, will eliminate, or 110 overcome to a marked degree, the tendency of this type of drill to become "balled up" in soft formation; and the joint provision 115 of double acting or two edged cutting members,—having cutting edges on both the advancing and following sides of the said members—and of means for ensuring their independent revolution, will secure a more 120 effective and rapid comminution of the material after it is cut away from the sides of the bore hole; and will also secure a more complete and continuous mixture and suspension of the finely divided material in the 130

currents of flushing water which are flowing downwardly over the forwardly advancing faces, and upwardly with the rearward following edges of the revolving cutters.

5 Having thus described my invention, what I claim as new and desire to protect by Letters Patent, is:

1. In a rotary boring drill, the combination with a drill head of two disc-shaped cutters set exactly opposite each other, and adapted to drill the full gauge of the hole, said cutters being rotatably mounted on axes transverse to the longitudinal axis of the drill head, the outer face of each cutter being dished to provide a cutting edge on the rearward following side thereof.

2. In a rotary boring drill, the combination with a drill head of two opposite disc-shaped cutters rotatably mounted on axes transverse to the longitudinal axis of the drill head and provided with cutting edges on both the forward side and the rearward following sides, the outer periphery of the said cutters being toothed on both edges in such manner as to assist in the rotation thereof.

3. A rotary boring drill comprising a head with two opposite cutting discs mounted on axes transverse to the longitudinal axis of the head, and having sharp cutting edges on both the outer and inner faces to shear away material in contact with both the advancing and following sides thereof.

4. A rotary boring drill comprising a head with two opposite cutting discs mounted on axes transverse to the longitudinal axis of the head and provided with sharp cutting edges on both faces thereof, the peripheral surfaces of the said cutters being shaped to conform to the curvature of the hole.

5. A rotary boring drill comprising a head and two opposite cutting discs mounted on the forward end thereof and so disposed thereon that their rearward following edges engage with the wall of the hole to be drilled, the periphery of the cutters being provided with teeth extending at an angle downwardly and backwardly from the rearward following edge and upwardly and backwardly from the forward advancing edge.

6. A rotary boring drill comprising a head and two opposite cutting discs mounted on the forward end thereof on axes transverse to the longitudinal axis of the head, the outer face of each cutter being recessed to provide a sharp cutting edge thereon, and both peripheral edges of the said cutters being shaped to conform to a common surface of revolution.

60 7. In a rotary boring drill, the combination of a head, a support at the lower end thereof, two bearing shafts secured on said support, and opposite cutting discs mounted on said bearing shafts, each of the said discs having a broad milling surface and a sharp

cutting edge on each side of said milling surface.

8. In a rotary boring drill, the combination of a head, and two oppositely disposed cutting discs rotatably mounted on the lower 70 end thereof, adapted to cut the full diameter of the hole, each of the said discs having a broad peripheral milling surface and a sharp cutting edge on each side thereof.

9. In a rotary boring drill, the combination of two opposite cutting discs rotatably mounted on shafts in the base thereof, the periphery of said discs being curved to conform to the shape of a hole and provided with sharp cutting edges on both faces to 80 engage the walls of the bore hole on both sides thereof.

10. In a rotary boring drill, the combination of a head and opposite cutting discs rotatably mounted thereon, the periphery of 85 each of said discs being rounded to conform to the shape of the hole, and the smaller outer portion thereof being extended laterally to form a comparatively sharp cutting edge.

90 11. A rotary boring drill comprising a head, with two oppositely disposed cutting discs mounted on axes inclined to the longitudinal axis of the head, each of said discs having sharp cutting edges on both the inner and outer sides thereof and toothed peripheral faces that are shaped to conform to the curvature of the hole.

12. In a rotary boring drill, the combination of a head and two oppositely disposed 100 disc-shaped cutters mounted on axes inclined to the longitudinal axis of the head and adapted to cut the full bottom of the hole, the peripheral faces of each of the said cutters being toothed and shaped to 105 conform to the curvature of the side and bottom of the bore hole.

13. A rotary boring drill comprising a head and two oppositely disposed cutting discs mounted on axes transverse to the 110 longitudinal axis of the head and inclined thereto, each of the said discs having sharp cutting edges on both sides thereof and peripheral faces which are toothed and shaped to conform to the curvature of the hole, the teeth on said peripheral faces being inclined downwardly and backwardly from the rearward following edge.

14. A rotary boring drill comprising a head and two oppositely disposed cutting 120 members, mounted at an angle to each other on the said head, the inner face of each member being substantially smooth and the outer face thereof being recessed to provide sharp cutting edges on both faces of the 125 said members.

15. In a rotary boring drill, the combination of a head and two oppositely disposed sets of cutting discs mounted rotatably in slots in the forward end of said head, each of 130

said sets of discs comprising two smooth contiguous sections capable of independent rotation and each section being provided with peripheral cutting teeth so inclined as to 5 effect a screw action to assist in the rotation thereof.

16. In a rotary boring drill, the combination 10 of a head, cutting discs journaled rotatably on bearing pins at the forward end of said head, lubricating means for said bearing pins which comprise a central tubular recess in the upper end of the said head and ducts leading from said recess to the said pins, a water pipe passing through 15 the said recess and threaded into the lower end thereof, and a cap engaging with said water pipe and closing the top of the said recess.

17. In a rotary boring drill, a head and 20 two disc-shaped cutters rotatably mounted

on axes in the base thereof; the said head having a longitudinal cavity closed at the bottom, oil ducts leading from said cavity to the cutter axes, a central tube in said cavity threaded into the closed end thereof, and a cover plate threaded on said tube, and adapted to close the top of said cavity. 25

18. In a rotary boring drill, the combination 30 of a head and two sets of cutting discs, each of the said sets being composed of two contiguous rotatable sections, one of the said sections being adapted to cut with the rearward following edge, and the other with the forward advancing edge, the inward thrust on one cutter being opposed to the 35 outward thrust on the other.

In testimony whereof, I hereunto affix my signature this the 8th day of May, A. D., 1920.

FRANK L. O. WADSWORTH.
